COFFEE TABLE

John O. Van Koert, New York, N. Y., assignor to Drexel
Furniture Company, Drexel, N. C., a corporation of Delaware

Application August 2, 1955, Serial No. 37,275

Term of patent 7 years

(Cl. D33—14)

The figure is a perspective view of a coffee table showing my new design, the opposite side and end thereof being the same in appearance as the side and end shown.
I claim:

The ornamental design for a coffee table, as shown and described.
